UNITED STATES PATENT OFFICE

2,314,532

PAPER FASTENER

Chester I. Wagner, Brooklyn, N. Y.

Application July 26, 1940, Serial No. 347,576

7 Claims. (Cl. 24—153)

This invention relates to a paper fastener and has special reference to a device for fastening papers such as letters, pamphlets, newspapers, magazines, and similar articles in book form for filing or the like.

More particularly this invention relates to a paper fastener comprising a base having spaced ears, one at each end, and a prong for each end of the base, each of the prongs having an aperture adjacent one end thereof for detachably receiving one of the ears to secure the prong relatively to the base, with the free ends of the prongs being adapted to be inserted through apertures in the paper to be fastened.

It is also contemplated by the present invention to provide a compressor for cooperation with the base, the free end of each of the prongs being adapted to be bent inwardly toward each other over the compressor and the compressor having means comprising openings adjacent the ends thereof or at the end edges for cooperating with the prongs for aiding in maintaining an assembled relation of the base and compressor.

In the usual paper fasteners of the type above described, the prongs thereof have been formed of sheet metal and either integrally or detachably secured to the sheet metal base. Both the base and the prongs therefor have been stamped of sheet metal and burred edges are inescapable in the stamping operation on the flat metal. Correspondents and file clerks, in the instance of handling sheet metal prongs of this type, together with the bases, have had to risk acquiring cut, scratched, or unsightly fingers from the usual burred edges thereof and danger of infection and serious disablement has been an ever-present peril. The present invention contemplates the use of a prong for each end of the base, the prong being flattened from wire stock. Such a construction provides smooth edges and, aside from the use of smooth round wire prongs, is perhaps the only practical manner of eliminating burred prongs and contributes a safety factor in the use of paper fasteners.

Individual prongs are formed from a continuous length of wire preferably of round cross section. In separating the wire to individual units of a desirable length, the parting tool may leave a burr at the end of the units resulting from the shearing cut. While each end of the prong attached to the base lies inside the base member and cannot scratch in handling by the hands nor can it catch on other files, the free end is exposed. Protection is afforded in handling by the provision of a cross rib adjacent each free

end of the prongs to deflect the fingers of file clerks and correspondents.

The use of a prong for each end of the base with the prong being detachably secured to the base in an extremely simple manner permits prongs to be quickly changed so that prongs of one, two, or more inches capacity are insertable when and if more than a minimum amount of bulk is accumulated in one file. The practice of buying complete fasteners with attached prongs is of course generally wasteful and inconvenient and the use of the detachable prongs with a single and convenient method of attaching the prongs to the base affords a maximum of economy. The purchaser may stock a substantial number of bases, compressors, and prongs, with the proportional number of shorter prongs being greater than the number of longer prongs, whereafter it will be more convenient to file the papers to be fastened on the shorter prongs until the actual growth of some of the files may demand greater capacity when the prongs of more substantial length may be substituted, the bases and compressors being retained.

One of the objects of this invention is to provide a paper fastener of the character hereinabove noted, in which each prong is easily and conveniently snapped on or detached from the base for purposes of interchangeability of prongs and of convenience in use.

Another object of this invention is to provide a paper fastener of the type indicated above which will afford a maximum of safety in the use thereof, thus eliminating danger of infection and serious disablement of the user.

Other objects and advantages will hereinafter be more particularly pointed out and for a more complete understanding of the characteristic features of this invention, reference may now be had to the following description when read together with the accompanying drawing, in which latter

Figure 1 is a plan elevational view of a paper fastener incorporating the features of this invention, the paper fastener being shown in use in fastening papers which latter are shown fragmentarily;

Fig. 2 is a longitudinal sectional view taken on the line 2—2 of Fig. 1;

Fig. 3 is a perspective view of the fastener and compressor assembly prior to the locking of the prongs of the base in position over the compressor;

Fig. 4 is a plan elevational view of a fragmentary portion of a base disclosing in detail

the manner in which the prong shown partially in section is fastened to the base;

Fig. 5 is an underneath plan of Fig. 4;

Fig. 6 is an enlarged sectional view taken on the line 6—6 of Fig. 4; and

Fig. 7 is a perspective view of one of the prongs embodied in the above-described figures.

Referring now more particularly to the drawing, the paper fastener shown therein incorporating the features of this invention comprises a base 10 having prongs 11 and 12 secured thereto, one for each end of the base, and a compressor 13 for co-operation with the prongs and base.

The base 10 is elongated and is preferably formed of thin sheet metal. Longitudinally extending embossments 14 and 15 are formed intermediate the width of the base adjacent each end thereof, the inside walls of the embossments preferably being continuous and communicating with each other as shown more particularly in Fig. 3. The material of the base 10 intermediate the embossments 14 and 15 may also be preferably embossed as at 16 for purposes of reinforcing the base and, although not necessary, may be desirable.

Each of the embossed portions 14 and 15 of the base 10 is provided with an ear 17 and 18, respectively, the ears being bent to form laterally extending pockets 19 and 20. The ears 17 and 18 are preferably cut and deformed from the material of the base 10 within the embossed portions and one end of each of the embossed portions 14 and 15 has an opening 21 and 22, respectively.

Each of the prongs 11 and 12 are formed of a wire stock flattened into a thin strip comprising a main body portion 23, and offset portion 24 adjacent one end of the main body portion. The end opposite to the offset end is provided with a raised portion 25 for purposes which will hereinafter be more particularly pointed out. An aperture 26 is disposed at the juncture of the offset portion 24 with the main body portion 23, the aperture 26 providing a closed loop at one end of the prong. The free end of the prong is adapted to be inserted through apertures in the paper or articles to be fastened while the other looped end of the prong is secured to the base. In flattening the ordinary round wire, the edges of the flattened strip resulting therefrom are smooth and prevent snagging or jagging the fingers by contact therewith.

Referring now more particularly to Fig. 4 of the drawing, the looped end of the prong is shown as being attached to the base, the loop formed by the apertured offset portion 24 being received in the laterally extending pocket 19 of the ear 17. The width of the ear is substantially the same as the aperture 26 of the prong and the offset portion is of such a height as to rest within the confines of the embossed portion of the base.

In order to assemble the prongs on the base, the free end of the prong 11 is inserted through the opening 21 whereafter the looped end is threaded into the laterally extending pocket 19, the free end of the ear being raised out of the opening from which it is cut to permit the apertured offset portion 24 forming the loop to pass therebeneath. After the looped end of the prong is engaged into the laterally extending pocket 19, the ear 17 is bent down into the position within the embossment 14 as shown particularly in Fig. 3 of the drawing if the resiliency of the metal does not function to perform the operation automatically. The extending free end of the prong

11 is thereafter bent upwardly at substantially right angles to the plane of the base within a notch 27 formed in an end edge of the base 10, a similar notch 28 being formed in the opposite end to receive therewithin the extending free end of the prong 12.

The compressor 13 is formed preferably of an elongated strip of sheet metal having longitudinally-extending guides along each side edge in the 10 form preferably of a channel produced by forming flanges 29 and 30 from material of the strip inwardly in a direction toward each other terminating in a spaced relation from each other and from the main body portion of the strip. A pair 15 of latching members 31 and 32 slidably engage the channels formed by the bent-over flanges 29 and 30, each of the latching members comprising a raised portion having laterally extending corrugations with side flanges 33 received in the 20 channels.

The compressor is provided with openings 34 and 35 preferably of substantially rectangular area adjacent each end thereof for receiving the free extending ends of the prongs 11 and 12, respectively. The prongs are bent over in a direction toward each other against the compressor 13 after extending through the apertures 34 and 35. In order to maintain the relation of the bent-over ends of the prongs to the compressor, the slides 30 31 and 32 are moved over the prongs, the latter being provided with the raised portions 25 for engaging the corrugations of the latching members to provide an interlocking resilient engagement therebetween. The raised portions 25 act also to 35 deflect the fingers of file clerks and correspondents from contact with any parting burrs on the free ends of the prongs during the handling thereof.

While but a single embodiment of this invention 40 is herein shown and described, it is to be understood that various modifications thereof may be apparent to those skilled in the art without departing from the spirit and scope of this invention and therefore the same is to be limited only 45 by the scope of the prior art and the appended claims.

I claim:

1. A paper fastener comprising a base having 50 inwardly extending ears one at each end, and having an aperture adjacent the fixed outer end of each ear, a flat metal prong for each end of said base, each of said prongs being insertable through one of said base apertures and having an aperture extending through the body of the metal adjacent one end thereof for detachably receiving 55 one of said ears to secure said prong relatively to said base, the free ends of said prongs being adapted to be inserted through apertures in the paper to be fastened.

2. A paper fastener comprising a base having 60 inwardly extending spaced ears one at each end, and having an aperture adjacent the fixed outer end of each ear, a flat wire prong for each end of said base, each of said prongs being insertable through one of said base apertures and having an aperture 65 extending through the body of the wire adjacent one end thereof for detachably receiving one of said ears to secure said prong relatively to said base, the free ends of said prongs being adapted to be inserted through apertures in the paper to be fastened.

3. A paper fastener comprising a base having 70 spaced ears one at each end, a prong for each end of said base, each of said prongs having a main body portion and an offset portion adjacent one

end thereof, and an aperture at the juncture of said offset portion for detachably receiving one of said ears to secure said prong relatively to said base, said main body portions of said prongs being adapted to be inserted through apertures in the paper to be fastened.

4. A paper fastener comprising an elongated base having spaced inwardly extending ears one at each end, a flat metal prong for each end of said base, each of said prongs having a main body portion and an offset portion adjacent one end thereof, said offset portion having an aperture extending through the body of the metal at the juncture of the offset portion with said main body portion to form a closed loop, said ears forming laterally extending pockets for receiving said loops for detachably securing said prong relatively to said base, the main body portions of said prongs being adapted to be inserted through apertures in the paper to be fastened.

5. A paper fastener comprising an elongated base having spaced inwardly extending ears one at each end, and an aperture adjacent each ear, a flat metal prong for each end of said base, each of said prongs having a main body portion and an offset portion adjacent one end thereof, said offset portion having an aperture extending through the body of the metal at the juncture thereof with said main body portion to form a closed loop, said ears having raised portions forming laterally extending pockets for receiving said loops for detachably securing said prong relatively to said base, the free ends of said prongs being adapted to be inserted through apertures adjacent said ears and thereafter through apertures in the paper to be fastened.

6. A paper fastener comprising an elongated base having spaced inwardly extending ears intermediate the ends thereof and a notch at each end edge, a flat metal prong for each end of said base, a compressor, each of said prongs having a main body portion and an offset portion adjacent one end thereof, said offset portion having an aperture extending through the body of the metal

at the juncture thereof with said main body portion to form a closed loop, said ears having raised portions forming laterally extending pockets for receiving said loops for detachably securing said prong relatively to said base, said base having an aperture between each of said notches and ears, the free ends of said prongs being adapted to be inserted through said base apertures and into said base notches, said prongs thereafter passing through apertures in the paper to be fastened and bent inwardly towards each other over said compressor.

7. A paper fastener wherein a base member is provided with means for selective locked attachment or ready removal of paper-penetrating prongs of varying lengths, comprising in combination a base member stamped from flat deformable sheet metal and embossed to provide a longitudinally rigid member having a central depression, said base member having prong-engaging and locking ears struck from the material thereof adjacent each end, portions of the base member beyond each of said ears being provided with prong-admitting apertures, prongs for each end of said base member, each of said prongs being formed from wire of circular cross section compressed to form a flat strap having smooth rounded edges, each prong including a main body portion and an offset locking portion adjacent one end thereof, said offset locking portion having an aperture extending through the body of the wire at the juncture thereof with said main body portion to form a locking slot for said prong-engaging and locking ears, each of said prongs being separately insertable into locked relationship with said base member by bodily passing the main body portion through one of the prong-admitting apertures therein, inserting the adjacent ear through the aperture in said offset portion, and deforming an intermediate part of the main body portion of said prong about the adjacent end of said base member.

CHESTER I. WAGNER.
